UNITED STATES PATENT OFFICE.

WILLIAM E. BELL, OF TULSA, OKLAHOMA, ASSIGNOR TO THE BELL WRENCH COMPANY, OF TULSA, OKLAHOMA.

RATCHET PIPE-WRENCH.

1,345,983.

Specification of Letters Patent.

Patented July 6, 1920.

Application filed November 28, 1919. Serial No. 340,982.

To all whom it may concern:

Be it known that I, WILLIAM E. BELL, a citizen of the United States, residing at Tulsa, in the county of Tulsa and State of 5 Oklahoma, have invented a new and useful Ratchet Pipe-Wrench, of which the following is a specification.

This invention bears reference to novel and useful improvements in wrenches and 10 more particularly to quick adjusting pipe wrenches.

Heretofore, a patent issued to one B. F. Woodward No. 788,388 dated April 25, 1905, and owned by me, disclosed the same 15 type of wrench as constitutes the subject of the present application. This wrench embodied a stationary jaw and a movable jaw, each having shanks and one provided with a series of ratchet-teeth engaged by a spring 20 actuated dog or pawl, so as to hold the jaws in adjusted relation, the jaws being also retained in operative relation, but the adjustment of one jaw relative to the other could only be accomplished with much difficulty 25 since the pawl had to remain in contact with the ratchet-teeth at all times.

Also, in my prior application filed July 25, 1919, under Serial No. 313,301, covering the same type of wrench and endeavoring to 30 overcome the objection of the prior patented construction, the teeth were arranged between opposed upstanding longitudinal ribs or shoulders but this necessitated that the device at this part be drop-forged and owing 35 to the sharp dies required to form the ratchet-teeth, the same was impractical as the dies would get dull too quickly and would require an unreasonable supply or number of dies and the expense incident 40 thereto would be prohibitive in order to render the manufacture and sale of the wrench practical or commercial.

The present invention therefore aims to obviate and overcome the above difficulties 45 by providing the jaw having the ratchet-teeth with longitudinal recesses or depressions along the side edges of the lower jaw shank outwardly of the ratchet-teeth and below the latter, and forming the heel of 50 the pawl with side flanges cut on eccentric circles so as to engage the bottom walls of the recesses or depressions so as to lift the pawl at its toe end from engagement with the ratchet teeth, upon the depression of the 55 rear end of the movable jaw shank through

the medium of a finger piece or thumb rest formed at said end to facilitate actuation of the wrench, thus permitting the movable jaw to be adjusted quietly and easily along the stationary jaw shank by substantially the 60 same pressure exerted to cause the disengagement of the pawl from the ratchet teeth and while so disengaged, during which time said flanges will slide along the bottom walls of the recesses or depressions, while 65 release of pressure will permit the pawl to automatically act to engage the ratchet-teeth and hold the movable jaw against further movements so as to properly fit a pipe or other object operated on. 70

A further object of the invention is to provide improved means for resiliently maintaining a slight separation of the jaw shanks adjacent to the stationary jaw, so as to permit necessary pivotal movement of the 75 movable jaw shank relative to the stationary jaw shank in the above operation and in such a manner as to eliminate crushing of pipes and particularly when unscrewing old or rusted joints, and to permit quick engagement and release of the jaws with and from the work. The invention further comprises a removable jaw face for the stationary jaw and means carried by the stationary jaw and its shank and movably receiving 80 and retaining the movable jaw shank in position, which means also serves to retain the jaw face in position and co-operates with resilient means between the jaw shanks tending to normally hold them separated. 85 90

With the above and other objects in view, which will appear as the description proceeds, the invention resides in the combination and arrangement of parts and in the details of construction hereinafter described 95 and claimed, it being understood that within the scope of what is claimed, changes in the precise embodiment of the invention shown can be made without departing from the spirit of the invention. 100

In the accompanying drawings:

Figure 1 is a side elevation partly broken away, of my improved wrench;

Fig. 2 is a fragmental side elevation partly broken away, of the wrench and showing 105 the parts in another position;

Fig. 3 is a sectional view taken on the line 3-3 of Fig. 2;

Fig. 4 is a sectional view taken on the line 4-4 of Fig. 2; and 110

Fig. 5 is a perspective view of a pawl employed with the device.

Referring to the drawing in detail, in which like reference characters designate corresponding parts throughout the several views, my improved wrench is shown as embodying a handle 10 having a shank 11 of rectangular cross section and formed with a stationary jaw 12. This jaw is formed with a transverse dove-tailed groove or key-way 13 receiving a projection 14 of similar cross section extending transversely from a removable toothed jaw face 15. The groove and projection extend throughout the width of the jaw and the face so that their side faces are disposed flush and the jaw face extends downwardly and rearwardly at an acute angle from the vertical.

Coöperating with the stationary jaw shank is a movable jaw shank 16 of a cross section corresponding to that of the stationary jaw shank 11, the movable jaw shank being formed with a jaw 17 constituting the movable jaw of the wrench, at its outer end, and having a reinforced serrated or toothed jaw face 18 also extending at an acute angle from the vertical and divergently from the other jaw face, the jaw face 18 being fixed or removable as desired. At the inner end of the movable jaw shank there is formed at the bottom, a rearwardly and upwardly curved finger-hold or thumb piece 19 adapted for depressing the movable jaw shank toward the stationary jaw shank for a purpose to be hereinafter made apparent.

The upper edge of the jaw shank 11 is provided with a longitudinal series of transverse ratchet-teeth or serrations 20 which terminate at spaced distances from the side faces of the shank outwardly of which the latter are formed with longitudinal depressions or recesses 21 from the top edge of the shank below the teeth, said recesses having smooth walls especially at the bottom and curving upwardly at their ends to meet the upper edge of the shank. The top edges of the teeth are in the plane with the top edge of the shank and thus, it is not only unnecessary to increase the breadth of the shank, but owing to the recesses formed as described, the teeth may be readily produced preferably by milling the same transversely of the shank on the portion between the recesses, thereby obviating the objection heretofore pointed out as a prelude to this description in reference to stamping the teeth and the troubles and expense incident thereto. The construction is greatly cheapened owing to the fact that a large number of the shanks clamp together, can be milled simultaneously to cut or form the ratchet teeth.

Coöperating with the ratchet teeth 20 is a pawl 22 the body of which is substantially circular and which is fitted in a correspond-

ingly shaped recess 23 in the lower edge of the movable shank 16. This recess extends transversely and communicates with the opposite edges of the shank with which edges or faces the ends of the pawl are flush, and the recess has a restricted portion at the bottom preventing the pawl from dropping out. The recess is provided with a forward extension 24 between the top wall of which and the pawl is disposed a small relatively weak compression spring 25 so as to hold the pawl at its edge or toe portion in engagement with the notches of the ratchet-teeth, the latter being so formed that their vertical walls face rearwardly and their inclined walls extend forwardly so that when the pawl is engaged with the right angular walls it will prevent the jaws from separating while serving to permit the pawl to ride over the teeth in the opposite direction when the movable jaw is adjusted toward the stationary jaw. The heel of the pawl is provided with side flanges 26 extended below the intermediate portion and cut on circles eccentric to the axis on which the pawl pivots so as to straddle the ratchet-teeth and when the thumb piece 19 is depressed, it will compress the spring 25 and rock the pawl on its pivot so as to lift the toe thereof from the ratchet teeth and bring the heel flanges against the bottom walls of the recesses 21, the eccentric formation of the latter sliding in the recesses in contact with the bottom walls thereof, raising the pawl clear of the ratchet teeth and permitting the movable jaw to be adjusted toward or away from the stationary jaw to suit the particular object being operated on or which the wrench must be set to fit. This movement may be accomplished by one hand while gripping the handle and engaging the thumb piece 19. At any rate, while the thumb piece, and thus the movable shank, is so depressed, this shank may be readily adjusted on the stationary shank so as to separate the jaws for engagement with an object and upon releasing the pressure, the jaws will be separated by the spring and properly engage the work as the jaw faces move toward each other.

It is to be understood that the jaws are normally disposed toward each other when the parts are in normal position and this is facilitated by an expansible spring member or plunger 27 mounted in one of the shanks, preferably the stationary shank at the top of the jaw 12 in a recess 28 provided therein so as to project without the recess and engage the bottom edge of the movable shank, thus holding the shanks normally in spaced parallel relation. In order to limit the spacing or separation of the shanks and still retain them so related as to coöperate in the manner described, a yoke or loop 29 is secured to the shank 16 near the thumb piece 130

19 and envelops both shanks and has its sides disposed at the ends of the pawl so as to prevent displacement of the latter. By retaining the loop in position through the 5 medium of plugs or rivet pins 30, the loop may be removed when desired or necessary, in order to replace or resharpen the pawl or to replace the spring, although, this would not ordinarily be required with the usual 10 wear and tear, except after a long period of use.

The removable jaw face 15 projects beyond the sides of the stationary jaw 12 and the projection 14 is narrower so that its 15 ends will be flush with the side faces of the jaw 12, and by this means the removable face can be retained in position through the medium of an inverted U-shaped yoke 31, the sides of which are secured to the sides 20 of the jaw 12 as indicated at 32 against the shoulders formed by the removable jaw face and outwardly of the securing means for the latter so as to prevent the same from becoming displaced. The bight of this yoke extends 25 over the top of the movable shank and the sides are also located at the sides of the stationary shank to which they are secured, and outwardly of the spring member 27 so as to protect and hide the latter.

30 From the foregoing, it is thought that the structure and operation of the device will be fully understood and therefore further explanation is deemed unnecessary.

Having thus described the invention, what 35 I claim is:

1. A wrench comprising a fixed jaw and shank, the latter having its upper edge provided with ratchet teeth and shoulders at either side of the teeth, a movable jaw having a shank, means for movably connecting the shanks, the shank of the movable jaw being recessed at its bottom edge and a spring actuated pawl pivoted in the recess to engage the ratchet-teeth and formed with 45 means to engage the smooth walls of the shoulders whereby to raise the pawl from engagement with the teeth and permit free sliding movement of the movable jaw relative to the fixed jaw with the engaging 50 means of the pawl moving along said walls.

2. A pipe wrench comprising a stationary shank having a handle and a jaw formed at the end thereof opposite to the handle, a movable shank having a jaw opposing the 55 stationary jaw, yokes carried by the shanks to permit the same to move relatively therein, one of the shanks being provided with a longitudinal series of transverse serrations and a depression outwardly thereof, means 60 holding the shanks in spaced relation, and a pawl pivoted in the other shank to engage the serrations and having an eccentric projection adapted on the pivoted movement of the pawl to ride in the depression and disengage the pawl from the serrations to per-

mit adjustment of the jaws relative to each other with the pawl so positioned and out of contact with respect to the teeth of the serrations.

3. A wrench comprising a shank having 70 a jaw and teeth along its top edge and flushed with said edge, there being recesses in said edge outwardly of the teeth and below the same, a movable shank having a jaw opposing the stationary jaw, yokes carried by each shank and slidably receiving the other shank, and a pawl pivoted to the movable shank and retained in position by one of the yokes and having a top portion normally engaged with the teeth, to hold 80 the jaws against separation, and having its heel portion formed with curved flanges at the sides spanning the teeth and cut on circles eccentric to the pivot of the pawl to engage the bottom walls of the recesses in 85 contact with the inner walls thereof upon depression of the movable shank whereby the latter may be freely slid on the stationary shank while the pawl is out of contact with respect to the teeth. 90

4. A wrench comprising a shank having a jaw and teeth along its top edge and flushed with said edge, there being recesses in said edge outwardly of the teeth and below the same, a movable shank having a jaw opposing the stationary jaw, yokes carried by each shank and slidably receiving the other shank, and a movable pawl carried by the movable shank and having eccentrically 95 formed flanges adapted to engage the walls 100 of the recesses to raise the pawl from engagement with the teeth to permit free movement of the movable shank and jaw relative to the stationary shank and jaw. 100

5. A wrench comprising a handle having 105 a shank and a jaw at the end opposite the handle, a removable jaw face transversely keyed in the jaw and projecting at either side to form shoulders, an inverted U-shaped yoke secured at either side of the jaw and 110 overlying the ends of the key, the forward edges of the yoke abutting the shoulders, a movable shank received by said yoke and having a jaw opposing the first jaw and at its opposite end a thumb piece, a yoke carried by the movable shank and engaging the other shank so as to receive the latter there-through, and means for holding the shanks 115 in adjusted relation.

6. A wrench comprising a handle having a 120 shank and a jaw at the end opposite the handle, a removable jaw face transversely keyed in the jaw and projecting at either side to form shoulders, an inverted U-shaped yoke secured at either side of the jaw and 125 overlying the ends of the key, the forward edges of the yoke abutting the shoulders, a movable shank received by said yoke and having a jaw opposing the first jaw and at its opposite end a thumb piece, a yoke car- 130

ried by the movable shank, and receiving the other shank therethrough, a spring member carried by the jaw end of the first shank and engaging through the edge thereof with the edge of the other shank to hold the shanks separated limited by the yokes, the first mentioned shank having transverse serrations forming parallel teeth and depressed walls formed out along the teeth, the other shank having a circular recess at the bottom and an extension forwardly thereof communicating with its sides of the shank at the sides of the adjacent yoke, a pawl having a circular portion pivoted in the recess and an extension to engage the teeth and flanges

to engage said depressed walls so as to raise the pawl from engagement with the teeth upon depression of the thumb piece and a spring between the pawl and the wall of the extension recess holding the pawl in an engaged position and cooperating with said spring member to hold the shanks normally separated.

In testimony that I claim the foregoing as my own, I have hereto affixed my signature in the presence of two witnesses.

WILLIAM E. BELL.
